CLAIM

The ornamental design for a soft tissue tool, as shown and described.

DESCRIPTION

FIG. 1 is a top view of the soft tissue tool of the present invention showing my new design;

FIG. 2 is a left side elevational view thereof;

FIG. 3 is a front elevational view thereof, the rear elevational view being a mirror image of the front elevational view;

FIG. 4 is a right side elevational view thereof;

FIG. 5 is a bottom view thereof; and,

FIG. 6 is a cross-sectional view thereof taken along line 6-6 of FIG. 3.
